UNITED STATES PATENT OFFICE.

PHINEAS N. FREASE, OF BOTHELL, WASHINGTON.

TOOL HOLDER.

Application filed April 15, 1922. Serial No. 553,063.

To all whom it may concern:

Be it known that PHINEAS N. FREASE, a citizen of the United States, residing at Bothell, in the county of King and State 5 of Washington, has invented certain new and useful Improvements in Tool Holders, of which the following is a specification.

The invention is directed to an improvement in hand tools of the type wherein an 10 independent handle is to be secured in fixed relation to the tool proper, and the invention comprehends a means whereby the handle may be effectively held in place against displacement during the use of the 15 tool.

In the drawings:

Fig. 1 is a view in side elevation, illustrating the invention in connection with an ordinary hammer.

20 Fig. 2 is an end elevation of the same.

Fig. 3 is a perspective view of the securing wedge.

The hammer here shown, at 1, is designed to represent any tool with which the invention may be utilized. The hammer head is formed with the usual handle eye 2 and the handle 3 is, for the purposes of this invention, cutaway on the lower edge 4 of that portion of the handle to be fitted with 25 in the eye, to provide by such cutaway portion, a wedge shaped opening between the lower edge of the handle end and the bottom of the hammer eye.

The wedge member 5 is adapted to be 30 driven in the wedge shaped opening described, this wedge member more or less accurately fitting the wedge surfaces throughout their contour and being formed on the side next the handle with serrations 35 to cooperate with the wood of the handle, as at 6, and formed on the opposite surface with teeth 7, to more or less engage with the material of the hammer head.

I have found by experiment that when 40 the handle is inserted into the head and a smooth faced holding member driven into the eye of the head, under ordinary circumstances, it is effective to hold the head securely upon the handle despite the tendency of the head to slip off the handle 45 when the tool is in use. If the tool be left, however, in a very dry atmosphere, such as an engine room or the like, for a consider-

able length of time, the wood of the handle is likely to shrink, and a holding wedge of 50 smooth surfaces is not so effective to hold the head to the handle. I have also found by experiment that if the holding wedge member 5 be serrated as indicated at 6, and teeth 7 cut upon its opposite surface, the 55 teeth being of very much smaller proportions than the serrations, that such a wedge is effective to at all times prevent the slipping of the head of the hammer from its handle. The relatively large serrations 6, 60 of course, contact with the wood of the handle as the wedge is being driven into its place as seen in Fig. 1, the wood, of course, not offering sufficient resistance to the serrations to prevent the driving in operation, 65 and if the wedge be so driven in, the upper surface of the recessed portion which coacts with the serrations will be roughened so as to result in great holding power between the wedge and the handle. The 70 teeth 7, as stated, are sharp and of very much smaller dimensions than the serrations, because those teeth contact with the metal of the head instead of with the wood 75 of the handle, and if the teeth were not relatively small in size, it would render it difficult to drive the wedge into place. The action of the teeth with respect to the metal of the head is similar, of course, to the action of the serrations 7 with respect to the 80 handle.

What I claim as new is:

The combination with a hammer head having an eye therethrough, and a handle having a wedge-shaped cutaway portion in 90 one edge of the part which passes through the eye, of a wedge-shaped member having serrations upon one of its faces and relatively fine teeth upon its opposite face, whereby the wedge member is adapted to be 95 driven in the recess in the handle so that the serrations will engage and embed in the handle and the teeth will engage the wall of the eye in the hammer head to effectively lock the handle against movement in the 100 hammer head.

In testimony whereof I affix my signature in the presence of a witness.

PHINEAS N. FREASE.

Witness:

R. L. KIRBY.
